US00D973859S

(12) **United States Design Patent** (10) **Patent No.:** **US D973,859 S**
(45) **Date of Patent:** **** Dec. 27, 2022**

(54) **FOOD PRESERVER**

(71) Applicant: **Electrolux Home Products, Inc.**,
Charlotte, NC (US)

(72) Inventors: **Eric Hitchcock**, Harrisburg, NC (US);
Josh Hanson, Huntersville, NC (US);
Belinda Zhang, Atlanta, GA (US);
Brent Curtis, Terrell, NC (US)

(73) Assignee: **Electrolux Home Products, Inc.**,
Charlotte, NC (US)

(**) Term: **15 Years**

(21) Appl. No.: **29/712,744**

(22) Filed: **Nov. 11, 2019**

(51) LOC (13) Cl. **23-04**

(52) U.S. Cl.

USPC **D23/367**
